BALANCE STAFF ASSEMBLY FOR WATCHES

William L. Brendler, Mankato, Minn.

Application August 7, 1941, Serial No. 405,847

7 Claims. (Cl. 58—140)

The invention relates generally to the art of watch making and primarily seeks to provide a novel form of balance staff which will enable replacement of broken staff pivots with great facility and without any danger of rendering untrue the assembly relation of the balance wheel, the hairspring, the hairspring collet, the roller table and the new pivots, or of damaging any of these parts.

It is well known to watchmakers that it is now customary to form the staff pivots which are received in the jewel bearings directly on the ends of the balance staff. The balance wheel, the hairspring, the hairspring collet, and the roller are secured in rigid assembly relation on the staff, usually by staking. It, therefore, becomes necessary, whenever a staff pivot is broken and must be replaced, to remove the hairspring and its supporting collet, the balance wheel and the roller table in order to remount them on a new balance staff which will provide the necessary new pivots. In the removal and remounting of these parts it is quite common to damage one or more thereof and it is extremely difficult, and to a watchmaker of inferior ability almost impossible, to reassemble the parts in absolutely true relation. It is obvious, therefore, that with the present equipment it is possible to repair a fine watch in which a balance staff has been broken only at considerable expense and time loss if the time-keeping efficiency of the watch is to be maintained. It is, therefore, an object of the present invention to provide a balance staff structure in which the pivots can be replaced without the necessity of removing and reassembling the individual parts originally mounted in rigid assembly on the balance staff.

Another object of the invention is to provide an improved balance staff structure upon which the balance wheel, the hairspring, the hairspring collet, and the roller table are mounted in rigid assembly, said staff including a tapered central bore and a tapered sliding staff equipped at its ends with pivots and removably mounted in and projecting at its ends from said bore.

Another object of the invention is to provide a balance staff structure of the nature stated which includes a removable sliding staff having pivots formed on the ends thereof and a bead thereon for definitely placing the pivots in proper position in the staff, said sliding staff also having a recess therein in which a retaining annulus or detent formed on the staff readily engages for the purpose of frictionally main-

taining the assembly of the balance staff and the sliding staff.

Another object of the invention is to provide in a watch structure a storage place in which a replacement sliding staff can be removably retained so as to be readily accessible to a watchmaker attempting to replace a broken staff pivot.

With the above and other objects in view which will more fully appear, the nature of the invention will be more clearly understood by following the description, the appended claims, and the several views illustrated in the accompanying drawing.

In the drawing—

Figure 1 is an enlarged central vertical section of a balance staff assembly embodying the invention.

Figure 2 is a view similar to Figure 1 with the sliding staff removed.

Figure 3 is an enlarged detail view illustrating the sliding staff per se.

Figure 4 is a detail perspective view of a watch bridge equipped with a storage groove so as to act as a receptacle for a spare sliding staff.

In the example of embodiment of the invention herein illustrated, the balance staff is constructed to include a tapered plug portion 5 from which a reduced diameter balance wheel mounting hub portion 6 is upwardly extended. An additionally reduced hairspring collet mounting hub portion 7 extends upwardly from the hub portion 6 and terminates in an upwardly tapered end 8.

Beneath the plug portion 5 the balance staff includes a downwardly extending and tapered shank portion 9, and the whole balance staff comprising the portions 9, 5, 6 and 7 is provided with an axial bore 10 which is slightly tapered in the upward direction as viewed in Figures 1 and 2.

A roller table 11 is rigidly secured upon the balance staff shank portion 9 as by staking as indicated at 12. The balance wheel generally designated 13 has its hub or central portion 14 rigidly secured upon the staff hub portion 6 as by staking as indicated at 15, and the hairspring assembly generally designated 16 has its center or supporting collet 17 rigidly secured upon the staff portion 7 as by staking or burnished over as indicated at 18. The parts 11, 13, 14 and 16, 17 form a permanent rigid assembly with the balance staff and this assembly need never be disturbed unless the individual parts thereof other than the assembly pivots hereinafter referred to become broken or in some manner dis-

placed from their perfect, true assembly relation.

The balance staff bore 10 is dimensioned to removably and snugly receive the tapered sliding staff 19 which is equipped at each end with the customary reduced pivot 20 designed to be received in a jewel bearing. At its lower end, and above the respective pivot 20, the sliding staff is equipped with an enlargement or bead 21 which abuts the lower end terminus of the roller table 11 and shank 9 to definitely place the sliding staff in the balance staff. The definite placement of this sliding staff is additionally secured by the provision of a recess or depression 22 at the upper end of the sliding staff, said recess being adapted to receive and be frictioned by the inwardly spun and longitudinally slotted end terminus or sleeve portion 23 of the tapered hub extension 8 of the balance staff. The inwardly spun portion 23 of the hub readily grips the sliding staff and retains it in place in the balance staff, but it is to be understood that the sliding staff may be readily removed from the bore 10 by a suitable downward pull thereon without in anywise disturbing or straining the perfectly true assembled relation of the hairspring, the balance wheel and the roller table.

In Figure 4 of the drawing there is illustrated a bridge 24 which is removed from its normal position in the watch case. The under surface of the bridge, or in fact any other suitable stationary part within the watch case can be equipped with a longitudinal groove 25 into which a spare or replacement sliding staff 19 can be removably placed, the groove being upset, as at 26, to removably retain said sliding staff. In this manner replacement of the improved form of sliding staff herein disclosed can always be assured, and in cases where a jeweler is not equipped with the particular form of sliding staff replacement, the owner of the watch needing replacement of a pivot need not be frustrated in his attempt at proper replacement or delayed in such replacement by the necessity of communication with the factory.

The advantages of the particular removable sliding staff structure and balance staff assembly herein disclosed over the one-piece balance staff structures now customarily employed in watches should be obvious. Under present known practices, when it becomes necessary to replace a broken pivot, it is, of course, necessary to replace the whole balance staff. This means that the hairspring assembly, the roller table and the balance wheel must be individually removed from the balance staff. In accomplishing this removal of parts, it is quite common to so badly damage the balance wheel by denting or bending the same out of true that it is practically impossible to perfectly true the same in the reassembly which must follow. It is possible also to damage the roller table during the removal thereof from the staff, and when removing the hairspring assembly by application of a suitable tool and a squeezing effort beneath the assembly collet, it very often happens that the hairspring is bent out of true. When this is done it means hours of work in an attempt to perfectly true the spring, and it is sometimes impossible to restore the parts to their original perfectly true condition. It will be obvious also that these tiny parts may become misplaced or lost during removal thereof.

After the parts above-mentioned have been removed from the broken balance staff, the watchmaker must look around for another staff

which will form a proper replacement for the broken unit. Perfect replacement units are not always available at the time the particular repair is demanded and delays are sometimes caused by the necessity of communication with the factory for proper replacements, and in some cases watches have been rendered inefficient by installation of improper replacements in an effort to avoid such delays.

10 After the proper balance staff replacements have been procured by the watchmaker, the roller table is properly mounted thereon. It then becomes necessary to remount, true and repose the balance wheel. The hairspring assembly is 15 then remounted and it becomes necessary to true the balance wheel and the hairspring assembly. The whole balance staff assembly is now ready 20 for replacement in the watch but this reassembly has been accomplished only after a considerable expenditure of time and labor, possibly several hours, and unless accomplished by a highly efficient watchmaker, it is quite likely that the timekeeping efficiency of the watch will be somewhat impaired. The structure herein disclosed 25 is designed for and is capable of avoiding all of the objections to the previous practices hereinabove noted.

In replacing broken pivots in the novel balance staff assembly structure herein disclosed and embodying the present invention, it is only necessary to apply nippers between the sliding staff bead 21 and the opposing surfaces of the staff shank 9 and roller table 11 to withdraw the sliding staff from its friction relation in the bore 10 30 at 22, 23. By now turning over the bridge 24 of the watch, the watchmaker can free the sliding staff by removal of the upsets 26 and the desired replacement sliding staff is immediately 35 available. This sliding staff can be slipped 40 through the bore into the position illustrated in Figure 1 without removing or disturbing the previous perfectly true relation of the roller table 11, the balance wheel 13, and the hairspring assembly 16 on the balance staff. By reason of the provision of this simple equipment, it is possible 45 to effect a saving of approximately 85% in time, labor and cost to the factory, the jobber, and the watch owner.

I am aware that attempts have been made heretofore to provide removable sliding staff structures, and I am aware also that although such structures have been known for many years they have never been found practical and the practices involving the replacement of broken balance staff pivots have remained unchanged up 50 to the present time. By the improved equipment herein disclosed, however, the necessary formation of the various parts of the balance staff assembly of individual parts and different materials is in nowise hampered and the particular formation of the tapered sliding staff 19 including the position retaining bead 21, recess 22 and friction detent 23 provides a structure which will avoid all of the objections of the present 55 practice and objectional prior art disclosures and provide a wholly practical balance staff assembly structure.

It is of course to be understood that the details of structure and arrangement of parts may be 60 variously changed and modified without departing from the spirit and scope of my invention.

I claim:

1. A balance staff assembly for watches comprising a balance staff element; unitary balance 65 wheel, roller table and hair-spring assembly

structures secured rigidly but removably in true assembly relation on said staff element; said balance staff element having an axial bore therethrough, a sliding staff element removably mounted in said bore having a length for extending at each end beyond said balance staff and having a pivot formed on each extended end, and means engaging and frictionally retaining said sliding staff element in said bore, said last named means comprising a detent carried by one said element and a detent receiving recess carried by the other of said elements.

2. A balance staff assembly for watches comprising, a balance staff; unitary balance wheel, roller table and hairspring assembly structures secured rigidly but removably in true assembly relation on said staff; said balance staff having an axial bore therethrough, a sliding staff removably mounted in said bore having a length for extending at each end beyond said balance staff and having a pivot formed on each extended end, and means engaging and frictionally retaining said sliding staff in said bore, said frictional engaging means comprising a recess formed in said sliding staff and an indentation formed on said balance staff and engageable in said recess.

3. A balance staff assembly for watches comprising, a balance staff; unitary balance wheel, roller table and hairspring assembly structures secured rigidly but removably in true assembly relation on said staff; said balance staff having an axial bore therethrough, a sliding staff removably mounted in said bore having a length for extending at each end beyond said balance staff and having a pivot formed on each extended end, and means engaging and frictionally retaining said sliding staff in said bore, said frictional engaging means comprising an annular recess formed in said sliding staff adjacent one pivot thereof and an inwardly spun annulus formed on the adjacent end of the balance staff and engageable in said recess.

4. A balance staff assembly for watches comprising, a balance staff; unitary balance wheel, roller table and hairspring assembly structures secured rigidly but removably in true assembly relation on said staff; said balance staff having an axial bore therethrough, a sliding staff removably mounted in said bore having a length for extending at each end beyond said balance staff and having a pivot formed on each extended end, said sliding staff being tapered and said bore being similarly tapered to very snugly receive said sliding staff, and means engaging and frictionally retaining said sliding staff in said bore, said frictional engaging means comprising an annular recess formed in said sliding staff adjacent one pivot thereof and an inwardly spun annulus

formed on the adjacent end of the balance staff and engageable in said recess.

5. A balance staff assembly for watches comprising, a balance staff; unitary balance wheel, roller table and hairspring assembly structures secured rigidly but removably in true assembly relation on said staff; said balance staff having an axial bore therethrough, a sliding staff removably mounted in said bore having a length for extending at each end beyond said balance staff and having a pivot formed on each extended end, said sliding staff being tapered and said bore being similarly tapered to very snugly receive said sliding staff, and means engaging and frictionally retaining said sliding staff in said bore, said frictional engaging means comprising an annular recess formed in said sliding staff adjacent one pivot thereof and an inwardly spun annulus formed on the adjacent end of the balance staff and engageable in said recess, and said sliding staff having a positioning bead thereon disposed at the end remote from its recessed end and abutting the adjacent end of the balance staff.

6. A balance staff assembly for watches comprising, a balance staff element; a balance wheel, a roller table and a hairspring assembly mounted on said staff element; said balance staff element having an axial bore therethrough, a sliding staff element removably mounted in said bore having a length for extending at each end beyond said balance staff and having a pivot formed on each extended end, and means engaging and frictionally retaining said sliding staff element in said bore, said last named means comprising a detent carried by one said element and a detent receiving recess carried by the other of said elements.

7. A balance staff assembly for watches comprising, a balance staff; a balance wheel, a roller table and a hairspring assembly mounted on said staff; said balance staff having an axial bore therethrough, a sliding staff removably mounted in said bore having a length for extending at each end beyond said balance staff and having a pivot formed on each extended end, said sliding staff being tapered and said bore being similarly tapered to very snugly receive said sliding staff, and means engaging and frictionally retaining said sliding staff in said bore, said frictional engaging means comprising an annular recess formed in said sliding staff adjacent one pivot thereof and an inwardly spun annulus formed on the adjacent end of the balance staff and engageable in said recess, and said sliding staff having a positioning bead thereon disposed at the end remote from its recessed end and abutting the adjacent end of the balance staff.

WILLIAM L. BRENDLER.
